UNITED STATES PATENT OFFICE.

WILLIAM G. CURTIS, OF SAN FRANCISCO, CALIFORNIA.

RAILWAY CONSTRUCTION.

SPECIFICATION forming part of Letters Patent No. 592,218, dated October 19, 1897.

Application filed April 1, 1897. Serial No. 630,320. (No model.)

To all whom it may concern:

Be it known that I, WILLIAM G. CURTIS, a citizen of the United States, residing at San Francisco, in the county of San Francisco and State of California, have invented certain new and useful Improvements in Railway Construction; and I do hereby declare the following to be a full, clear, and exact description of said invention, such as will enable others skilled in the art to which it most nearly appertains to make, use, and practice the same.

This invention relates to improvements in railway construction, and more particularly to the splice-plates for joining the ends of the rails.

The objects which this invention has in view are, first, to produce a construction in which the rail is reinforced and in which the reinforcing member is held rigidly against the under side of the head of the rail and against the under side of the flange or base of the same, and, second, to provide a construction whereby the reinforcing member is maintained in its rigid position against the traffic strain.

In the drawings, Figure 1 is a perspective view of a rail-joint, the same being formed with splice-plates constructed in conformity with this invention. Fig. 2 is a plan view of the same looking from underneath the rail. Fig. 3 is a sectional view of a rail and the splice-plates, taken on the line X X in Fig. 2. Fig. 4 is a diagrammatic view of a rail-joint as constructed with the old fish-plates, the form in which the parts are shown being an exaggeration for the purpose of illustration.

Heretofore the splice-plate which has been substituted for and developed from the old fish-plate has consisted in the throwing out of a side flange from the bottom of the fish-plate to overhang the upper part of the flange or base of the rail. This construction was provided to avoid the bend by increasing the depth of the fish-plate; but as this form of connection has but one upwardly-resisting bearing-surface to each plate—to wit, that under the head of the rail—it soon becomes loosened by wear and ceases to be effective. This latter construction has been supplemented by a construction known as the "continuous-angle" plate, which consists of the

old fish-plate having a continuation of the side flange set out from the bottom thereof to extend over the top and under the bottom of the flange or base of the rails, the bottom section or continuation being thought to reinforce the resistance to the vertical traffic strain. This latter construction has proved to be a great advantage over both those preceding, but it has been found that the bottom section extended below the base of the rail is too flexible to enable it to assist the upper upwardly-resisting bearing-surface, and that this form of plate wears and becomes loosened in the same manner as above set forth.

It is the purpose of the present invention to produce a construction which embodies the benefits derived from what has been styled the "continuous-angle plate," with those of the last type wherein have been provided the vertical extension below the flange of the rail. This construction consists in the vertical plate A, the continuous extension of the same, B, and the downset portion of the latter C. The vertical plate A is practically of the same construction as that now in use, having the shoulders A' and A² adapted and shaped to bear tightly under the head and over the flange or base of the rail with a hollowed-out middle portion A³. The extension B differs from the continuous style in that in its present construction these extensions are brought to a very close approximation at their meeting edges under the flange or base of the rail, with the purpose of permitting as wide an extension of this feature of the angle-plate under the flange of the rails as possible, and at the same time providing thereby more material wherewith to form the downset portion C. The downset portion C is swaged or struck down from the extension B directly beneath the joint of the meeting rails.

In drawing or swaging downward the portion C the metal of the extension B is slightly stretched, and there is produced between the level part of the extension B and the vertical portion C the intermediate metal D, which is caused to assume the V shape shown in the drawings. This interposed metal D corrects all tendency which the vertical portion C might otherwise have toward lateral movement in avoiding vertical strains. By so con-

structing the downward-extended portion C the unsupported lower portion of this plate between the adjacent ties becomes in effect a girder and the adjacent surfaces are held 5 firmly against the under side of the base of the rail, giving for each plate two effective upwardly-resisting bearing-surfaces—viz., at e and at b—thereby greatly decreasing the rate of wear, thus prolonging the useful service 10 of the joint.

In making the bend in the extension B, inside which the side of the flange is to fit, it may be bent a little more acutely within the angle than the flange, so as to necessitate 15 the forcing of the thickest part of the flange next to the web of the rail between the wings of the bent extension. It is by this means that a rigid contact may be obtained by the extension B against the under face of the 20 flange of the rail; but this is not essential, provided a good fit may be obtained without so bending. The means for securing the ends of the rail within the grasp of these angle-plates is the same as that commonly in use, 25 consisting in the bolts E E, passed through

the angle-plate and web of the rail on either side of the joint thereof.

Having thus described this invention, what is claimed is—

A splice for the joints of rails consisting of 30 vertical plates adapted to bear against the under side of the head of the rail and having continuous extensions around and under the flange or base of the rail to near the middle thereof, the said extensions having the center 35 portion struck down and out from the inner edge to a line between the inner and the outer edge to form a vertical reinforcement to bear against the under side of the base of the rail, and held in position by the stretched portions 40 of the metal connecting the reinforcing with the horizontal portion, substantially as described.

In testimony whereof I have hereunto set my hand this 19th day of March, 1897.

WILLIAM G. CURTIS.
